CLAIM

The ornamental design for a cooking range as shown and described.

DESCRIPTION

FIG. 1 is a perspective view of a first embodiment of a cooking range;

FIG. 2 is a front view of the cooking range of FIG. 1;

FIG. 3 is a top plan view of the cooking range of FIG. 1; FIG. 4 is a right side view of the cooking range of FIG. 1; FIG. 5 is a left side view of the cooking range of FIG. 1; FIG. 6 is a perspective view of a second embodiment of the cooking range;

FIG. 7 is a front view of the cooking range of FIG. 6;

FIG. 8 is a top plan view of the cooking range of FIG. 6;

FIG. 9 is a right side view of the cooking range of FIG. 6; FIG. 10 is a left side view of the cooking range of FIG. 6; FIG. 11 is a perspective view of a third embodiment of the cooking range;

FIG. 12 is a front view of the cooking range of FIG. 11;

FIG. 13 is a top plan view of the cooking range of FIG. 11; FIG. 14 is a right side view of the cooking range of FIG. 11; and,

FIG. 15 is a left side view of the cooking range of FIG. 11. The broken lines in the drawings depict portions of the cooking range that form no part of the claim design.

1 Claim, 15 Drawing Sheets
